(57) **CLAIM**

The ornamental design for a commuter shoe bag, as shown and described.

DESCRIPTION

FIG. 1 is a front view of a commuter shoe bag of the present invention when the top of the bag is in a closed configuration.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a first perspective view thereof.

FIG. 8 is a second perspective view thereof.

FIG. 9 is a perspective view of the commuter shoe bag of the present invention when the top of the bag is in an open configuration.

FIG. 10 is another perspective view of the commuter shoe bag of the present invention when the top of the bag is in an open configuration.

FIG. 11 is a perspective view of the commuter shoe bag of the present invention when two side pockets of the bag are both in an open configuration.

FIG. 12 is a perspective view of the commuter shoe bag of the present invention when one side pocket of the bag is in an open configuration and the other side of pocket of the bag is in a closed configuration.

FIG. 13 is another perspective view of the commuter shoe bag of the present invention when one side pocket of the bag is in an open configuration and the other side of pocket of the bag is in a closed configuration; and,

FIG. 14 is a top view of the commuter shoe bag of the present invention when the top of the bag is in an open configuration.

The broken line showing of certain portions of the commuter shoe bag is included for the purpose of illustration only and forms no part of the claimed design.
